(57) **CLAIM**

The ornamental design for a digital refrigerant meter as shown and described.

DESCRIPTION

FIG. 1 is a front, left, and top perspective view of the digital refrigerant meter, showing my design;

FIG. 2 is a rear, right, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of an encircled area labeled "9" in FIG. 1; and,

FIG. 10 is an enlarged view of an encircled area labeled "10" in FIG. 3.

The broken lines depict portions of the digital refrigerant meter that form no part of the claimed design. The dot-dash broken lines shown in FIGS. 1, 3, 9, and 10 are included for the purpose of indicating areas of the enlarged views and form no part of the claimed design.
